UNITED STATES PATENT OFFICE.

GEORGE B. STREIT, OF DETROIT, MICHIGAN.

EASEL.

1,020,583.

Specification of Letters Patent. Patented Mar. 19, 1912.

Application filed June 9, 1911. Serial No. 632,104.

To all whom it may concern:

Be it known that I, GEORGE B. STREIT, a citizen of the United States, residing at Detroit, county of Wayne, State of Michigan, have invented a certain new and useful Improvement in Easels, and declare the following to be a full, clear, and exact description of the same, such as will enable others skilled in the art to which it pertains to make and use the same, reference being had to the accompanying drawings, which form a part of this specification.

This invention relates to easels for supporting advertising cards, or other articles.

It has for its object an easel which is adapted to so interlock that the parts may not become separated although it is subjected to knocks and falls.

In the drawings:—Figure 1, is a view of the easel attached to a card and in collapsed condition, ready for shipment. Fig. 2, is a side elevation of the easel showing the locking-tongue in the position which it assumes when straightened so that the eye will fit over the projection and knob, and showing in dotted lines the position of the tongue after the eye has been fitted over the projection and knob and the bendable tongue has resumed its normal position. Fig. 3, is a rear perspective showing the easel ready for use. Fig. 4, is a view of a tandem-tongue easel, collapsed and ready for shipment. In this easel the knob on the projection is omitted. Fig. 5 is a side elevation of the easel shown in Fig. 4 with parts broken away to show the bendable tongue.

The easel may be made with either one back-stay member or two back-stay members. In the drawings the one back-stay member variety is shown. It is cut from the blank of the shape shown in Fig. 1 which comprises a rectangular vertical strip included within the lines $e-b$, $b-c$, $c-d$, and $d-c$, to which is added at one side a triangular strip A which forms the back-stay member, and which is bounded in the blank by the lines $a-e$, $e-b$, and $b-a$. Line $b-e$, which separates the triangular strip from the rectangular strip is scored from b to f and from f to h . However, a curved cut is described from f to h indenting into the rectangular strip forming a rib-stay C. From the point h on the continuing line $h-e$, the blank is cut a short distance along said line and then indents into the back-

stay member A with a curved line $k-l$, forming a lobe D. The cut is continued from the point l across the rectangular strip to the point j . The piece included by this cut $f-h$, $h-k$, $k-l$, $l-j$, $c-b$, forms a locking-tongue B, which has an integral connection with the back-stay member A at $b-f$. The remaining portion of the vertical rectangular strip $l-e$, $e-d$, $d-j$, forms a supporting-plate F. The opposite edge, $b-a$, of the back-stay member A has a cut-away portion which is included between the points g and h . This cut-away portion has a bottom edge which is inclined somewhat at an angle to the outside edge. Rising in about the center of the cut-away portion and flush with the opposite edge is the projection 2, which is shown in Figs. 1, 2, and 3 with the knob 2' on its under side. This knob, however, may be omitted, as in Figs. 4 and 5, and its particular use in connection with the locking feature will be explained hereafter. In Figs. 4 and 5 a similar effect is secured by making the outlying portion of the under edge of the projection 2 farther from the hinging axis of the tongue than the inward portion the distance gradually lessening toward the bottom of the notch 4. The projection 2 forms with the opposite sides of the cut-away portion, notches 3 and 4. The upper boundary of the notch 3 indicated in the drawings will be called the indenting edge 1. This indenting edge is an important feature of my invention and its function will be explained more at length hereafter. In the lobe D, and in line with the line $b-e$ in the blank, is cut an eye I. A circular aperture E is cut in the locking-tongue B to be used as a means of grasping the tongue.

The operation of the easel in locking is as follows: The back-stay member is bent to a right-angular relation with the tongue B and the supporting-plate F. The tongue B is then grasped by the finger, inserted through the aperture E, and swung back to the projection 2 as shown in Fig. 2. The position of the eye I with reference to the projection 2 is so calculated that it will just register over the top of the projection 2. When the free portion of the tongue is straightened, the eye may be readily fitted over the projection 2 and knob 2', and when the straightening tension is abated, the locking tongue assumes its ordinary position and draws the lobe under the knob 2'. In

Figs. 4 and 5 this engagement is brought about by calculating the position of the indenting edge 1 so that the bendable tongue in its usual bent position would not quite 5 reach so as to slip over the indenting edge 1. The calculations are such that when the tongue is straightened, the upper edge of the lobe D will just slip over the indenting edge. When the straightening tension is released 10 the tongue B will resume its normal tendency, bringing the upper edge of the lobe into such close frictional engagement that the tongue can rarely be disengaged without applying lifting-effort directly 15 thereunder.

The rib-stay C is, as shown by the drawing, formed by concaving the locking-tongue. This stay adds considerable rigidity to the back-stay member. It is also a feature of 20 this easel that the back-stay member and locking-tongue interlock at a point in the rear and below the center where experiment shows that reinforcement is most needed.

25 Figs. 4, and 5, also show the tandem-tongue locking means. Each tongue may be made to lock over the knob or the frictional engagement may be depended upon alone. The tandem-tongue is desirable and useful 30 in the larger easels as it adds both locking security and reinforcing strength.

What I claim is:—

1. An easel, having in combination a back-stay member, having on one edge a projection provided with a knob, a locking-tongue 35 connected with the opposite edge of said back-stay member and having a tendency to normally lie at the base of said back stay member and provided with a lobe having 40 an eyelet, the said locking-tongue being adapted to be straightened so that the said eyelet will fit over the projection, and its knob and the tongue, having a tendency to resume its normal position, will draw the 45 substance of the lobe surrounding the eyelet

below the knob of said projection, substantially as described.

2. An easel, having in combination a back-stay member provided on one edge with a notch having opposed faces, and a locking-tongue connected with the opposite edge of said back-stay member and having a tendency to normally lie at the base of said back stay member and provided with a lobe engaging between the opposing faces of the 50 notch, the said engagement being enhanced by the drawing tendency of said locking-tongue, substantially as described.

3. An easel, having in combination a back-stay member, a locking-tongue integral at 60 one end with one edge of the said back-stay member, and at the other end having a locking engagement with said back-stay member, a rib-stay integral with the back-stay member foldable with respect thereto and 65 located intermediate the ends of said tongue, substantially as described.

4. An easel, having in combination a back-stay member, a bendable locking-tongue connected with one edge thereof and having a 7 tendency to normally lie at the base of said back stay member, and at its other end engaging against the opposite edge of said back-stay member, said back-stay member being provided, with an edge portion angularly rising from said last mentioned edge, and a lobe on said tongue so located as to just fit over the said rising edge portion by straightening the tongue, and adapted to be drawn up into close engagement with said 8 edge portion when the said tongue is allowed to resume its normal tendency, substantially as described.

In testimony whereof, I sign this specification in the presence of two witnesses.

GEORGE B. STREIT.
